Fig. 4

FIGURE 1 is a perspective view of a mobile air traffic control tower embodying my design;

FIGURE 2 is a plan view of the same;

FIGURE 3 is a side view of the same as seen from the side opposite to the side seen in FIGURE 1, a portion being broken away for convenience of illustration; and

FIGURE 4 is an end view of the same as seen from the end opposite to the end seen in FIGURE 1.

The design is characterized by a long main portion and an upper portion over the top of the main portion adjacent one end thereof, the length of the upper portion being a minor portion of the length of the main portion, the height of the upper portion being substantially less than the height of the main portion, the sides of the upper portion being inclined downwardly and inwardly to lines located well within the vertical planes of the sides of the main portion.

The dominant features of my design are shown in solid lines.

I claim:

The ornamental design for a mobile air traffic control tower, as shown and described.
